CLAIM

We claim the ornamental design for the eating utensil, as shown and described.

DESCRIPTION

FIG. 1 is an isometric front, side and top view of our eating utensil with chopsticks attached and shown in dashed outline. FIG. 2 is an enlarged isometric view, similar to that of FIG. 1 showing a front, side and top view of my eating utensil, less the chopsticks.

FIG. 3 is an orthographic side view of my eating utensil, both side views being the same.

FIG. 4 is an orthographic front view of our eating utensil.

FIG. 5 is an orthographic rear view of our eating utensil.

FIG. 6 is an orthographic top, downward looking view, of our eating utensil; and,

FIG. 7 is an orthographic bottom, upward looking view of our eating utensil.

The broken lines shown in the drawings are for illustrative purposes only and form no part of the claimed design.
